DESIGN FOR A SHOE

Margaret Mullin, New York, N. Y.

Application August 11, 1934, Serial No. 52,904

Term of patent 3½ years

To all whom it may concern:

Be it known that I, MARGARET MULLIN, a citizen of the United States, residing in New York, in the county of New York and State of New York, have invented a new, original, and ornamental Design for a Shoe, of which the following is a specification, reference being had to the accompanying drawing, forming part thereof.

Figure 1 is a plan view of a shoe, showing my new design.

Figure 2 is a side perspective view of the shoe.

The dominant feature of the present invention resides in the ornamental effect produced by attaching a bow of the appearance shown adjacent the front portion of the shoe in such a position as to provide a sector-shaped opening therebelow.

I claim:

The ornamental design for a shoe, as shown and described.

MARGARET MULLIN.
